UNITED STATES PATENT OFFICE

HANS P. SCHEEL AND HANS P. SCHEEL, JR., OF TACOMA, WASHINGTON

PULP GRINDING STONE

Application filed August 29, 1931. Serial No. 560,178.

This invention relates to the construction of grinding stones designed primarily for use in grinding wood pulp.

The primary object of the invention is the provision of means whereby warm water or steam may be used to supply or develop the necessary expansion to maintain the stone at a uniform temperature throughout the entire mass during the seasoning or hardening thereof, or may provide means whereby cold water or air may be used to reduce the internal heat in the mass of plastic material during the curing process thereby providing a stone which is exceptionally strong and durable.

Another object of the invention is to provide means for reinforcing the stone, the reinforcing means acting to anchor the grinding ring of the stone.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a grinding stone constructed in accordance with the invention.

Figure 2 is a longitudinal sectional view through the grinding stone.

Figure 3 is a sectional view through the grinding ring of the grinding stone, the reinforcing wire being shown as wound spirally over the body portion.

Referring to the drawings in detail, the grinding stone comprises a core or body portion indicated by the reference character 5, the same being provided with a central opening 6 to receive the shaft, on which the grinding stone is mounted.

The grinding stone is constructed of plastic material such as an especially prepared concrete, constructed for grinding purposes, around which the reinforcing wire rings 7, are positioned. As shown in Fig. 2 the rings 7 are arranged in spaced relation to form a series of hoops.

The reference character 8 designates the grinding ring of the stone, which is also constructed of an especially prepared plastic material to withstand wear to which the stone is subjected, in grinding pulp. As shown, the reinforcing wire 7 is also imbedded in the grinding ring 8, securely anchoring the grinding ring in position.

A plurality of pipes indicated by the reference character 9 extend longitudinally of the body portion of the grinding stone, the ends being open to the atmosphere so that water, steam or other liquid may be passed through the pipes, heating or cooling the body portion to a uniform temperature throughout the entire mass.

Due to the heating of the body portion to a uniform temperature, an exceptionally hard and durable stone is produced which is capable of withstanding more heat than the natural stone now in common use.

After the seasoning of the stone, these pipes 9 may be filled with a plastic material, or the pipes may be removed, and the openings filled, thereby providing a solid mass.

As shown by Figure 3 of the drawings, the reinforcing wire, which is indicated by the reference character 10, is wound spirally over the body portion, to increase the strength of the stone.

It is also to be understood that although the hoops have been shown as constructed of round material, other cross-sectional material may be used.

Should it be desired to maintain the body portion cool, during the setting of the plastic material of which the body portion is con-

structed, cold water or air may be forced through the pipes 9.

Having thus described the invention, what is claimed is:

5 A method of constructing grinding stones, consisting in providing a core of plastic material, embedding pipes in the core, the ends of the pipes terminating at the side faces of the core, and finally passing a medium through the pipes to change the temperature 10 of the plastic material as the plastic material is setting.

10 In testimony that we claim the foregoing as our own, we have hereto affixed our signatures.

15 **HANS P. SCHEEL**
HANS P. SCHEEL, JR.
